WINDOW STRUCTURE

Raymond C. Pratt, Chicago, Ill.

Application November 19, 1953, Serial No. 393,037

4 Claims. (Cl. 20—53)

The present invention relates to a novel closure, and more particularly to a novel window structure.

As is well known, large buildings, such as office buildings, usually are subject to a considerable maintenance expense due to the labor involved in washing windows. With the usual window structure heretofore known, it is necessary for the window washer to stand on the window sill supported by safety strips and the like in order to wash the outside of the window. This involves considerable labor expense because of the time required to climb in and out of the window and also because of the rather high cost of the labor due to the hazardous nature of the job. Another disadvantage of window structures heretofore in general use is that the window may be only partially opened for ventilating or other similar purposes. It is, therefore, an object of the present invention to overcome these disadvantages of prior window structures by providing a novel window structure which may be easily washed on both sides without requiring the washer to climb through the window and which may be moved to an open position with the window opening substantially completely unobstructed to provide maximum ventilation.

Another object of the present invention is to provide a novel window structure of the above described type which may be easily moved to and from opened and closed positions and which is effectively sealed against entry of atmospheric moisture and the like when in the closed position.

A more specific object of the present invention is to provide a novel window structure of the above described type with novel means for locking the window sash in a closed position.

Other objects and advantages of the present invention will become apparent from the following description and the accompanying drawings, wherein:

Fig. 1 is a perspective view illustrating the outside of a window structure embodying the principles of this invention with the window sash in a closed position;

Fig. 2 is a perspective view similar to Fig. 1, but showing the window sash in an open position;

Fig. 3 is an enlarged fragmentary elevational view showing the inside of a lower portion of the novel window structure in greater detail;

Fig. 4 is an enlarged vertical cross sectional view taken along line 4—4 in Fig. 1;

Fig. 5 is an enlarged fragmentary vertical cross sectional view taken along line 5—5 in Fig. 2;

Fig. 6 is an enlarged fragmentary cross sectional view taken along line 6—6 in Fig. 1;

Fig. 7 is a fragmentary horizontal cross sectional view taken along line 7—7 in Fig. 3;

Fig. 8 is a fragmentary horizontal cross sectional view taken along line 8—8 in Fig. 3;

Fig. 9 is a fragmentary vertical cross sectional view taken along line 9—9 in Fig. 7;

Fig. 10 is a perspective view illustrating a locking element of the present invention;

Fig. 11 is an enlarged fragmentary vertical cross sec-

2

tional view showing a novel construction feature of this invention in greater detail;

Figs. 12, 13, and 14 are somewhat diagrammatic vertical cross sectional views showing how various shades or heat and light filters may be used with the novel window structure; and

Fig. 15 is a cross sectional view taken along line 15—15 in Fig. 14.

Referring now more specifically to the drawings, where like parts are designated by the same numerals throughout the various figures, a window structure 12 embodying the principles of this invention is shown best in Figs. 1 and 2. This window structure includes a generally rectangular frame 14 having upper and lower frame members 16 and 18 and vertical frame members 20 and 22, which frame members are adapted to be secured within a window opening in a wall 24. A window sash 26 is pivotally mounted by means described below for movement from a closed position in the plane of the window frame, as shown in Fig. 1, to an open position, as shown in Fig. 2. In addition, in accordance with a feature of this invention, the window sash may be pivoted at least about 180° so as to enable both sides of the sash to be presented toward the interior of the building for easy cleaning.

The frame members 16 through 22 of the window frame are preferably formed from extruded aluminum, but it is understood that any other suitable material may be used. As shown best in Fig. 4, the frame member 16 includes a pair of spaced legs 28 and 30 which are interconnected by an integral web 32 in a manner to provide the frame member with a generally H-shaped cross section. Flanges 34 and 36 extend from the upper edges of the legs 28 and 30 and are provided with suitable apertures for receiving bolts or the like 38 which are used to secure the frame member to the building wall 24. The H-shaped frame member is adapted to receive therein window sealing means 40 which is engageable with an edge of a closed window sash to provide a substantially weathertight seal. By referring to Figs. 4 and 7, it is seen that the frame members 18 and 20 are formed of cross sections identical to the frame member 16 and receive window sealing devices 42 and 44 which are substantially identical to the above mentioned sealing means 40. It is understood, of course, that the window frame member 22 is identical to the frame member 20 and contains a sealing means identical to the sealing means 44. Since all of these sealing means are identical, only the sealing means 40 will be described in detail.

The sealing means 40 includes an elongated plate member 46 which extends for the full length of the upper edge of the window sash. The plate member 46 is slidably mounted between the legs 28 and 30 of the frame member by means of a pin 48 threaded or otherwise secured to the plate member, as at 50, and slidably extending through a suitable aperture 52 provided in the web 32 of the frame member. The pin 48 is provided with an enlarged head 54 which prevents the pin from coming out of the aperture in the web 32, and preferably a washer 56 is positioned between the head 54 and the web 32 to prevent injury to the web. It is, of course, understood that the present invention contemplates the use of a plurality of pins similar to the pin 48 spaced at convenient intervals 55 along the length of the plate member 46. The plate member 46 is provided along opposite longitudinally extending margins thereof with flanges 58 and 60 which are adapted slidably to engage the frame member legs 28 and 30 to guide the plate member for sliding movement and to prevent the plate member from tilting relative to the window frame. The plate member 46 is also provided with outwardly projecting and longitudinally extending ribs 62

and 64 adjacent opposite edges thereof and a similar centrally located rib 66 for cooperative engagement with the window sash in the manner described below. A longitudinally extending sealing pad 68 of rubber or any other suitable material is secured to the outer face of the plate member 46 and between the ribs 62 and 66, and a substantially identical sealing pad 70 is disposed between the ribs 64 and 66. The elongated plate member is resiliently biased outwardly with respect to the frame member for engagement with the sash by means of one or more compression springs 72 which are preferably disposed around the pins 48.

The sash 26 includes upper and lower frame members 74 and 76 and side frame members 78 and 80. As shown best in Figs. 9 and 11, adjacent frame members are provided with bevelled mating ends which are retained together by means of an angle bracket 82 and a plurality of screws 84 passing through apertures in the frame members and threaded into the bracket. In order to draw the ends of adjacent frame members, such as the lower frame member 76 and the side frame member 78, together to provide a rigid and tight joint, the angle bracket is provided with screw receiving apertures 86 and 88 which are slightly offset from apertures 90 and 92 in the frame members 76 and 78, respectively. Thus, as the screws 84 having bevelled entering ends are inserted through the apertures in the frame members and started into the apertures in the bracket in the manner shown in Fig. 11, the ends of the frame members are drawn tightly together.

The window sash frame members are preferably formed from extruded aluminum, and each is provided with a cross sectional shape substantially identical to the cross sectional shape of the frame member 74 which will be described in detail. As shown best in Figs. 4 and 6, the frame member 74 is generally rectangular in cross section and is provided with an upper wall 94, a lower wall 96, and side walls 98 and 100. The junctions between the side walls and the lower wall of the frame member are formed to provide channels 102 and 104 adapted to receive edges of glass window panes 106 and 108. In order to provide a weather and airtight seal between the glass and the frame members, elongated sealing elements 110 and 112 of rubber or any other suitable material and having a generally U-shaped cross section enclose the peripheral edge of the glass window panes 106 and 108, respectively, and seat in the channels of the frame members. The glass window panes are retained in position by means of clamping plates 114 and 116 secured to the side walls of the frame member 74 by any suitable means, such as screws and the like. These clamping plates are preferably constructed of aluminum and it is understood that substantially identical clamping plates are also affixed to the side walls of the frame members 76, 78 and 80 in order to clamp the entire peripheral edges of the glass panes.

The upper wall 94 of the frame member 74, as well as the corresponding walls of the other sash frame members, is provided with a convex outer surface. A plurality of elongated grooves 118, 120, and 122 are formed in the convex surface for receiving and cooperating with the ribs 62, 64, and 66, respectively, extending from the plate member of the locking device. Thus, when the window sash is in the closed position shown in Fig. 4, the ribs enter the grooves to form a partial seal and to retain the sash in the closed position. In addition, the entry of the ribs into the grooves permits the concave sealing members 68 and 70 to press against the convex surface of the frame member, whereby a substantially air and weathertight seal is obtained. An additional preliminary seal is provided to prevent entry of rain water and the like between the edges of the window frame and the sash. This preliminary seal includes a flexible elongated strip 124 of rubber and the like secured to the outer side of the sash frame member 74 by a plurality

of suitable screws 126. An elongated block or strip 128 is secured to or made integral with the outer wall 28 of the window frame member 16 and is provided with a notch 130 for receiving the edge of the rubber strip 124. Thus, it is seen that any rain water or the like will be directed past the joint between the window frame and the sash and onto the outer window pane. The space between the sides and lower edge of the sash and the window frame is also sealed by flexible rubber strips 132, 134, and 136 shown best in Figs. 3 and 4. It should be noted that the ribs and the complementary grooves of all of the sealing means plate members and window sash frame members are generally V-shaped so that upon application of a predetermined pressure tending to open the window in the manner described below, the ribs are cammed out of the grooves to permit the window sash to open.

In accordance with a feature of the present invention, the window sash is pivotally mounted for rotation about a central axis thereof by suitable means, whereby the sash may be rotated at least about 180° to present the outer surface of the sash toward the interior of the building for easy cleaning. Furthermore, by rotating the sash about 90° from its closed position to the open position shown in Fig. 2, it is seen that the entire window opening is left substantially unobstructed so as to provide maximum ventilation. The means for pivotally mounting the sash is shown best in Fig. 6 and includes a pivot pin 138 centrally located with respect to the window frame and the sash and extending through aligned apertures 140 and 142 in the web portion 32 of the window frame and the sealing plate member 46, respectively. The pivot pin is provided with an enlarged head 144 to limit downward movement thereof and preferably a reinforcing and bearing plate 146 is disposed between the head and the web 32 and secured to the web by screws 148 or other suitable means. The lower end of the pivot pin also extends through an aperture 150 in the upper wall 94 of the sash frame member and is threaded into a reinforcing block 152, which block may be conveniently secured to the sash frame member wall 94 by suitable screws 154. With this structure, it is seen that the pivot pin 138 not only mounts the sash for pivotal movement about the central and vertical axis of the sash, but also supports the weight of the sash. Since the weight is applied to the pivot pin in tension, forces tending to bend the pin are reduced to a minimum, thereby permitting the use of a pin having a relatively small diameter and substantially eliminating any possible need for relatively complicated and heavy bearing means for guiding and reinforcing the pivot pin. In order to restrain the lower edge of the window sash for proper pivotal movement, a second pivot pin 156 is provided in axial alignment with the pivot pin 138. The pivot pin 156 is threaded or otherwise secured to the outer peripheral wall of the sash frame member 76, as at 158, and slidably extends through aligned apertures 160 and 162 in the plate member of the sealing means 40 and the transverse web of the window frame member 18, respectively. Since the pivot pins are located at the central axis of the sash, it will be understood that the sash may easily be rotated through 180°, and in certain instances may even be rotated a full 360° if desired.

While the operation of the above described window structure is believed to be clear, a short description of such operation is as follows. Starting with the window sash located in the closed position shown in Figs. 1 and 4, it is understood that the sash is normally retained in this position by interengagement between the ribs on the sealing plates located in all four window frame members and the complementary grooves located in all four of the sash frame members. In order to open the window, it is merely necessary to apply a predetermined force with the hand to a portion of the sash adjacent

a vertical margin thereof, whereupon the sealing plate members are cammed away from the sash and against the action of their respective compression springs until the ribs disengage from the grooves. Upon disengagement of the ribs from the grooves, the window sash may be freely moved to any desired position. It is understood, of course, that the preliminary sealing strips 124, 132, 134, and 136, which are made of rubber or the like, are sufficiently flexible to eliminate any substantial interference with pivotal movement of the sash.

In many instances, it may be desirable to lock the sash positively in its closed position, and in accordance with the present invention, such locking may be obtained with the structure shown best in Figs. 8, 9 and 10. This locking structure includes a shaft 164 rotatably mounted between opposite sides of the window frame member 20. In the illustrated embodiment, the shaft is provided with a pair of cam portions 166 and 168 adjacent its opposite ends which fit within notches 170 and 172 in the sealing plate member 174 of the sealing means 44. The shaft 164 is mounted at its opposite ends by eccentrically located stub shaft portions 176 and 178, so that upon rotation of the shaft, the cam portions 166 and 168 positively force and lock the sealing plate member 174 in secure engagement with the window sash frame member 78. The locking shaft 164 may conveniently be operated by a suitable tool, not shown, insertable into a non-circular socket 180 in the end of the shaft. Since the locking shaft 164, when properly located, positively prevents movement of the sealing bar away from the sash, it is seen that the interengaging ribs and grooves effectively retain the sash in the closed position regardless of the amount of pressure applied to the sash. It is understood, of course, that, when necessary, a plurality of the locking shafts 164 may be spaced along the window frame member 20, and, if desired, additional shafts, not shown, may be located in the opposite window frame member 22.

From the above description, it is seen that the present invention has provided a window structure, wherein the window sash may be moved to present both sides of the sash toward the interior of the building for easy cleaning. With this structure, the expense of cleaning the windows may be materially reduced, and a further saving may be obtained by eliminating the necessity for cleaning blinds or shades which are usually associated with the window. In order to accomplish this latter result, a Venetian blind structure has been inserted between the spaced parallel glass window panes 106 and 108, and since the space between the window panes is sealed against entry of moisture, dust, and the like in the manner described above, the Venetian blind structure never needs cleaning. In the illustrated embodiment, the Venetian blind structure includes upper and lower tilt bars 182 and 184 which are pivotally mounted between opposite vertical sides of the sash frame. A plurality of slats 186 are spaced between the tilt bars and have forward and rear edges secured to a pair of spaced tapes 188 and 190. The tapes, which are preferably continuous, encircle the tilt bars and are fixed thereto so as to move upon rotation of the tilt bars to adjust the angular position of the slats.

Suitable means is provided for rotating the tilt bars of the blind structure, and this means is shown best in Figs. 3, 4, 7, and 9. The tilt bar actuating means includes a shaft 192 journaled in the sash frame member 78 and having an actuating knob 194 secured to an outwardly extending end portion thereof. The inner end of the shaft rigidly carries a worm 196 meshing with a worm wheel 198. The worm wheel is fixed on a shaft 200 which has one end journaled in a wall of the sash frame, as at 202 (see Fig. 9), and the opposite end, which is non-circular in cross section, is inserted into a socket member 204 fixed to the lower tilt bar 184. It is obvious, of course, that the shaft 202 must extend

through an aperture, such as the aperture 206 in the inner wall of the sash frame member 20, and in order to seal this aperture, a conical stopper member 208 constructed of cork, rubber, or other suitable material tightly surrounds the shaft and securely seats on the conical wall of the aperture. With this structure, it is seen that the Venetian blind may easily be adjusted merely by turning the hand knob 194.

In Figs. 12 through 15 there are illustrated several modified forms of the present invention wherein the above described Venetian blind structure between the glass panes has been eliminated and been replaced by a blind or filter structure secured to the window sash so that it will move with the sash. More particularly in Fig. 12 a conventional Venetian blind 220 is secured to the inwardly facing side of the upper sash frame member 74 as at 222. This Venetian blind structure may be of any well known design and need not be described in detail. In Fig. 13 a conventional roll-up type cloth window shade 224 is supported between brackets 226 fixed to the upper sash frame member 74.

In Figs. 14 and 15 there is illustrated a modified form in which a filter structure 228 is secured to the outwardly facing side of the window sash to control the amount of light and heat radiating through the window. This filter structure may include a screen 230 mounted within a frame 232, which frame is hinged to the vertical window sash member 78 as at 234. A latching device 236 is mounted on the opposite vertical sash member 80 to retain the filter frame in the closed position against the window sash shown in solid lines in Fig. 15. With this structure the light filter may be conveniently swung away from the window sash for any desired purpose such as cleaning the window pane. The screen 230 may be of any well known louvre type wire mesh or it may be made of any other material capable of filtering heat and light. In addition, the filtering structure 228 might be replaced by a plurality of louvres, not shown, adjustably mounted directly on the window sash.

From the above description, it is seen that the present invention has provided a novel window structure, wherein the sash may be easily positioned so as to present both sides thereof for relatively rapid and economical cleaning, thereby providing considerable reduction in maintenance costs. Furthermore, it is seen that the present invention has provided a window structure having a pivotally mounted sash with novel and relatively simple means for obtaining a substantially air and weathertight seal between the sash and the window frame. It is also seen that the present invention has provided a window structure with novel and relatively simple means for positively locking the sash in the closed position.

While the preferred embodiment of the present invention has been shown and described herein, it is obvious that many structural details may be changed without departing from the spirit and scope of the appended claims.

I claim:

1. A window structure comprising a generally rectangular frame including channel portions facing inwardly around the opening therethrough, a generally rectangular sash member complementary in size and shape to the opening through said frame, means pivotally mounting said sash member within said frame for movement between open and closed positions, an elongated member reciprocable in each channel portion of the frame, means yieldably biasing the elongated members toward a position for engagement with the edges of the sash member, the edges of said sash member and said elongated members having mutually interengaging projection and recess means with mutually cooperating camming surfaces operable with the sash and elongated members in substantial registering position during initial opening and final closing of the sash member to shift the elongated members away from the sash member when the sash member

is initially moved toward open position and when finally approaching closed position, and weather sealing means and secured to the member carrying the said projection means and disposed adjacent the said projection means in position to seal against the other member and clear of the mutually cooperating camming surfaces, and said weather sealing means being relieved from contact with said other member under cooperation of said camming surfaces when the sash member is initially moved toward open position and when finally approaching closed position whereby the weather sealing means is subjected substantially only to the pressure of the biasing means substantially without friction or rubbing contact between the sash member and elongated members during open and closing movements of the sash member.

2. A window structure as claimed in claim 1, wherein the projection means is on the elongated members and the weather sealing means is carried by the said elongated members clear of the camming surfaces on the projection means.

3. A window structure as claimed in claim 1, wherein the projection means comprises projecting elements spaced laterally of the member carrying the same with the weather sealing means disposed between the projecting elements and clear of the camming surfaces thereon.

10 15 20 25

4. A window structure as claimed in claim 1, wherein the projection means comprises a plurality of elongated ribs spaced apart laterally of the member carrying the same and with the weather sealing means disposed between the said ribs and clear of the camming surfaces thereon.
